L. J. D. HEALY

PAVING BLOCK

Filed May 19, 1924

LEON J. D. HEALY
INVENTOR

BY *Robert D. Harvey*
ATTORNEY

UNITED STATES PATENT OFFICE.

LEON J. D. HEALY, OF MILWAUKEE, WISCONSIN, ASSIGNOR TO THE FISK RUBBER COMPANY, OF CHICOPEE FALLS, MASSACHUSETTS, A CORPORATION OF MASSACHUSETTS.

PAVING BLOCK.

Application filed May 19, 1924. Serial No. 714,303.

To all whom it may concern:

Be it known that I, LEON J. D. HEALY, a citizen of the United States, and a resident of Milwaukee, in the county of Milwaukee, and State of Wisconsin, have invented certain new and useful Improvements in Paving Blocks, of which the following is a specification.

My invention relates to paving blocks and more particularly to such blocks formed of rubber or a rubber composition.

Blocks made according to my invention while particularly adapted for use in factories, courtyards, and bridges may be advantageously used in paving streets and roadways.

The objects of my invention will be evident from the specification and claims.

In the drawings which illustrate one embodiment of my invention:

Figure 1 is a perspective view of such block.

Figure 2 is a fragmentary sectional view showing the manner of securing the blocks to the foundation and

Figure 3 is a plan view further illustrating one manner of laying.

Referring to the drawings the block, preferably formed of rubber, fiber or a combination of the two of any desired degree of hardness, is indicated generally at 1. I have illustrated a rectangular block but it will be understood that it may take any desired shape. The block is provided along one edge with a wedge shaped tongue 2, the upper face 3 of which is narrower than lower face 4. The opposite side of the block is provided with a groove 5 corresponding in shape to tongue 2. The lower and wider face 6 of groove 5 is provided with a longitudinal recess 7 adapted to receive blind securing or anchoring means 8 as shown in Figure 2. Recess 7 is positioned, as shown,

adjacent the outer edge of face 6 and so that it clears the upper edge of the block. 45

As will be evident the position of recess 7 permits the blocks to be quickly and accurately secured in position while the securing means are completely hidden and protected by the tongue 2 which interlocks with the 50 adjacent block or blocks.

The block may be laid on any type of foundation 9 and the securing or anchoring means 8 may take any form suitable to the foundation. Where it is desirable to water- 55 proof the pavement the blocks are best laid in asphalt or common tar paving cement.

To secure a maximum interlocking action, the blocks are preferably laid in the manner shown in Figure 3 but may be arranged in 60 any desired relation.

Having described one form of my invention I claim:

1. A paving block formed of a rubber composition and provided on opposite edges 65 with complementary tongue and groove, the lower face of the latter being provided with a longitudinal recess.

2. A paving block formed of a rubber composition and provided on opposite edges 70 with complementary tongue and groove, said tongue and groove being so shaped that the lower face of the latter extends beyond the edge of the block and a longitudinal recess 75 in said extended portion.

3. A paving block comprising a body portion provided along one edge with a groove and along the opposite edge with a complementary tongue, the lower face of said groove being extended beyond the upper face of the 80 body portion, and a longitudinal recess in said extended face.

In testimony whereof I have signed my name to the above specification.

LEON J. D. HEALY.
